United States Patent

Des. 240,688
Patented July 27, 1976

240,688

BOOKCASE OR THE LIKE

David P. Zagaroli, 2035 11th Street Court NW,
Hickory, N.C. 28601

Filed Apr. 16, 1975, Ser. No. 568,511

Term of patent 14 years

Int. Cl. D6—04

U.S. Cl. D6—168

The figure is a front perspective view of the bookcase or the like showing my new design.

The opposite side of the bookcase is substantially a mirror image of that shown.

The back and top of the bookcase are substantially plain and unornamented.

I claim:

The ornamental design for a bookcase or the like, as shown and described.
